CLAIM

The ornamental design for a vessel boot as shown and described.

DESCRIPTION

FIG. 1 is a perspective view of the vessel boot.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a perspective view of the vessel boot in use with an example drinking vessel.

The broken lines shown in the Figures represent unclaimed subject matter and form no part of the claimed design with dash-dot-dash lines reflecting boundaries of the claimed design and dash-dash-dash lines reflecting unclaimed features of the design.
